CYLINDER LOCK

Frederick W. Kenney, Bloomfield, N. J.

Application February 24, 1936, Serial No. 65,504

14 Claims. (Cl. 70—419)

My invention relates generally to cylinder locks, and particularly to a cylinder lock involving a plurality of cylinders requiring to be successively engaged and operated by a key, and an important object of my invention is to provide a cylinder lock of this character which is positively resistant to picking.

Another important object of my invention is to provide a cylinder lock of the character indicated above which contains sets of locking pins which produce the locking of the various cylinders together, the said sets of pins being capable of re-arrangement and re-proportioning so as to effect different combinations requiring different keys.

Another important object of my invention is to provide a cylinder lock of the character indicated above wherein certain of the cylinders thereof must be operated by the key into predetermined positions before the key can come into engagement with other cylinders thereof in a position to be capable of being operated to unlock the lock.

Other important objects of my invention will be apparent from a reading of the following description in connection with the drawings, wherein for the purposes of illustration I have shown a preferred embodiment of my invention.

In the drawings:—

Figure 1 is a front end elevational view of the embodiment showing in dotted lines the initial positions of the keyways of certain cylinders.

Figure 2 is a longitudinal vertical sectional view taken through Figure 1 approximately on the line 2—2.

Figure 3 is a longitudinal sectional view taken through Figure 1 approximately on the line 3—3.

Figure 4 is a top plan view of Figure 1 showing the locking pins in the initial positions of their cylinders.

Figure 5 is a front end elevational view of the intermediate cylinder showing the cut-out portion of the keyway therein.

Referring in detail to the drawings, the numeral 5 generally designates the exterior casing of the lock which includes the integral or suitably fastened face plate 6 and the eccentric bore 7, in which eccentric bore is rotatable the outer cylinder 8 which has its front end cut out as indicated by the numeral 9 behind the face plate

to accommodate the spring 10 which has one end attached to the inner or front cylinder 11 and has its remaining end attached to the cylinder 8 in such a way as to urge the cylinder 11 toward its initial position.

Rotatable within the cylinder 8 and in an accommodating opening in the face plate 6 is the front cylinder 11 which has the eccentrically located longitudinal keyway 15 into which project the lower and longer sections of three-section pins 16, 17, and 18, which have sections slidable into accommodating openings in the cylinder 8 and into spring holding bores in the casing 5 in which tensioning springs 25, 26 and 27 are located.

Also rotatable within the cylinder 8 and axially inwardly of the cylinder 11 is the intermediate cylinder 12 which has a keyway 19 which is normally aligned with the axially inward end of the keyway 15, into which keyway 19 projects the lower and longer section of a three-section pin 28, which pin works through an accommodating opening in the cylinder 8 and into a bore in the outer casing 5 in which is located the tensioning spring 29. The pins 16, 17 and 18 and 28 have intermediate pin sections which are adapted to be moved so as to have their upper and lower ends flush with the inner and outer sides of the cylinder 8 when the key is inserted in the keyway 15 and extended into the keyway 19, so that the cylinders 11, 12 and 8 are disconnected from the outer casing 5 at this point, allowing cylinders 11 and 12 to be rotated toward the right or in a clockwise direction by the key, so as to align the keyways 15 and 19 with the forward end of the keyway 20 which is located in the rear or final cylinder 13.

The final cylinder 13 has a boss 14 which is engageable with a spring latch mechanism. The front end of the cylinder 13 is cut away as indicated by the numeral 24 to accommodate the spring 23 which has one end connected to the intermediate cylinder 12 and its opposite end connected to the final cylinder 13 so as to tension these two cylinders relative to each other.

With the key (not shown) inserted through the keyways 15 and 19 and the cylinders 11 and 12 rotated toward the right as far as they will go by manipulation of the key, the lower sections of the pins 16, 17 and 18 come directly under

larger pins 31, 32, 33, and the lower section of the pin 28 under a larger diameter pin 34. The pins 31 to 34 are each composed of two pin sections and are larger in diameter than the pins 16, 17, 18 and 28, so that the radially inward ends of the pins 31 to 34 always ride on the exterior of the cylinders 11 and 12 and cannot enter the holes in which the smaller pins work. With the small pins 6, 17, 18 and 28 under the large diameter pins 31 through 34, the key is passed into the keyway 20 of the final cylinder 13. This passage or movement of the key raises the upper ends of the lower sections of the pins 31 to 34 to a position flush with the radially outward side of the cylinder 8, so that the cylinders 8, 11 and 12 are then free for rotation relative to the outer casing 5 at this second point.

Springs 35, 36, 37 and 38 operate in receiving bores in the outer casing 5 to press the larger pins 31 to 34 against the exterior of the cylinders 11 and 12.

As the key is inserted in the keyway 20 in the final cylinder, the pins 21 and 22 which extend into the keyway 20 are forced radially outwardly against the tension of the springs 30 and 39 in receiving openings in the outer casing 5 until the upper ends of the lower sections of the pins 21 and 22 are flush with the exterior of the cylinder 8. This frees the cylinder 8 completely from casing 5, for further rotation, in a clockwise direction of cylinders 8, 11, 12 and 13, which now operate as a unit, to cause the lug 14 on the final cylinder to retract the spring latch bolt to which it may be operatively connected.

It is to be noted that the pins 21 and 22 always connect the final cylinder 13 and the cylinder 8, since these pins are never brought to such a depressed position as to become flush with the exterior of the final cylinder 13, but the upper ends of these pins continually extend into the receiving openings in the cylinder 8.

Withdrawal of the key, in locking the lock, from the keyway 20 in the final cylinder permits the spring of the latch bolt or other such mechanism to rotate the final cylinder 13 back to its initial position and as cylinder 13 and cylinder 8 are continuously pin connected, cylinder 8 is likewise carried back to its initial position.

The tension furnished by the spring 23 between the final cylinder 13 and the intermediate cylinder 12 produces rotation of the intermediate cylinder 12 toward its initial position, while the spring 19 operates to turn the front cylinder 11 toward its initial position. Figure 5 shows the manner in which the keyway 19 of the intermediate cylinder 12 has one side cut away as indicated by the numeral 40 on a line with the rib 41 in the keyway.

The purpose of this cut away portion is to prevent the obtaining of purchase by any bar or rod which can be inserted through the keyways 15 and 19 for the purpose of raising the pins in these keyways in an attempt to pick the lock. It is obvious that if such bar or "jigger" be placed as far as the keyway 19, it can obtain a purchase on the right hand side of the keyway, but no unlocking is produced by pressing against this side of the keyway, on account of the arrangement of the intermediate cylinder for unlocking rotation in the opposite direction. Further it is obvious that due to the cut away 40 no purchase can be had by the "jigger" on the left hand side of the keyway 19, so that it is practically impossible by the use of any such means to pro-

duce the rotation of the intermediate cylinder 12 to such a position as to line up the keyway 19 with the keyway 20 in the final cylinder, such alignment being necessary to producing raising of the pins 34, 22 and 21 to release the cylinders 5 concerned for operation of the cylinder 13.

Although I have shown and described herein a preferred embodiment of my invention, it is to be definitely understood that I do not desire to limit the application of the invention thereto, 10 and any change or changes may be made in the materials, and in the structure and arrangement of the parts, within the spirit of the invention and the scope of the subjoined claims.

What is claimed is:—

1. A cylinder lock of the character described comprising a relatively stationary casing formed with a bore, an outer tubular cylinder rotatable in said bore, a front cylinder, an intermediate cylinder, and a final cylinder rotatably mounted 20 in the bore of said tubular outer cylinder, a locking bolt operating element on said final cylinder, first means engaging said final cylinder, said outer tubular cylinder, and said casing for holding said final cylinder and said outer tubular cylinder and said casing from rotating relative to each other in a locked condition of the lock, second means in said casing and said outer tubular cylinder preventing relative rotation of said outer cylinder and said casing in a locked condition of the lock.

2. A cylinder lock of the character described comprising a relatively stationary casing formed with a bore, an outer tubular cylinder rotatable in said bore, a front cylinder, an intermediate 35 cylinder, and a final cylinder rotatably mounted in the bore of said tubular outer cylinder, a locking bolt operating element on said final cylinder, first means engaging said final cylinder, said outer tubular cylinder, and said casing for holding said final cylinder and said outer tubular cylinder and said casing from rotating relative to each other in a locked condition of the lock, second means in said casing and said outer tubular cylinder preventing relative rotation of said 40 outer cylinder and said casing in a locked condition of the lock, third means in said casing, said outer tubular cylinder, and said front cylinder preventing relative rotation thereof while the lock is in a locked condition.

3. A cylinder lock of the character described comprising a relatively stationary casing formed with a bore, an outer tubular cylinder rotatable in said bore, a front cylinder, an intermediate cylinder, and a final cylinder rotatably mounted 55 in the bore of said tubular outer cylinder, a locking bolt operating element on said final cylinder, first means engaging said final cylinder, said outer tubular cylinder, and said casing for holding said final cylinder and said outer tubular cylinder and said casing from rotating relative to each other in a locked condition of the lock, second means in said casing and said outer tubular cylinder preventing relative rotation of said outer cylinder and said casing in a locked condition of the lock, fourth means in said casing, said outer tubular cylinder and said intermediate cylinder preventing relative rotation thereof in a locked condition of the lock.

4. A cylinder lock of the character described 70 comprising a relatively stationary casing formed with a bore, an outer tubular cylinder rotatable in said bore, a front cylinder, an intermediate cylinder, and a final cylinder rotatably mounted in the bore of said tubular outer cylinder, a locking 75

bolt operating element on said final cylinder, first means engaging said final cylinder, said outer tubular cylinder, and said casing for holding said final cylinder and said outer tubular cylinder and 5 said casing from rotating relative to each other in a locked condition of the lock, second means in said casing and said outer tubular cylinder preventing relative rotation of said outer cylinder and said casing in a locked condition of the 10 lock, third means in said casing, said outer tubular cylinder, and said front cylinder preventing relative rotation thereof while the lock is in a locked condition, fourth means in said casing, said outer tubular cylinder and said intermediate 15 cylinder preventing relative rotation thereof in a locked condition of the lock.

a locked condition of the lock.

5. A cylinder lock of the character described comprising a relatively stationary casing formed with a bore, an outer tubular cylinder rotatable in said bore, a front cylinder, an intermediate cylinder, and a final cylinder rotatably mounted in the bore of said tubular outer cylinder, a locking bolt operating element on said final cylinder, first means engaging said final cylinder, said outer tubular cylinder, and said casing for holding said final cylinder and said outer tubular cylinder and said casing from rotating relative to each other in a locked condition of the lock, second means in said casing and said outer tubular cylinder preventing relative rotation of said outer cylinder and said casing in a locked condition of the lock, third means in said casing, said outer tubular cylinder, and said front cylinder preventing relative rotation thereof while the lock is in a locked condition, fourth means in said casing, said outer tubular cylinder and said intermediate cylinder preventing relative rotation thereof in a locked condition of the lock, said front cylinder, said intermediate cylinder, and said final cylinder being formed with respective keyways into which said first, third, and fourth means project operatively.

16. A cylinder lock of the character described comprising a relatively stationary casing formed with a bore, an outer tubular cylinder rotatable in said bore, a front cylinder, an intermediate cylinder, and a final cylinder rotatably mounted in the bore of said tubular outer cylinder, a locking bolt operating element on said final cylinder, first means engaging said final cylinder, said outer tubular cylinder, and said casing for holding said final cylinder and said outer tubular cylinder and said casing from rotating relative to each other in a locked condition of the lock, 50 second means in said casing and said outer tubular cylinder preventing relative rotation of said outer cylinder and said casing in a locked condition of the lock, third means in said casing, said outer tubular cylinder, and said front cylinder preventing relative rotation thereof while the lock is in a locked condition, fourth means in said casing, said outer tubular cylinder and said intermediate cylinder preventing relative rotation thereof in a locked condition of the lock, 55 said front cylinder, said intermediate cylinder, and said final cylinder being formed with respective keyways into which said first, third, and fourth means project operatively, said front cylinder and said intermediate cylinder having initial positions in which their keyways are aligned and in which their keyways are out of alignment with the keyway of said final cylinder.

7. A cylinder lock of the character described comprising a relatively stationary casing formed with a bore, an outer tubular cylinder rotatable

in said bore, a front cylinder, an intermediate cylinder, and a final cylinder rotatably mounted in the bore of said tubular outer cylinder, a locking bolt operating element on said final cylinder first means engaging said final cylinder, said outer tubular cylinder, and said casing for holding said final cylinder and said outer tubular cylinder and said casing from rotating relative to each other in a locked condition of the lock, second means in said casing and said outer tubular cylinder preventing relative rotation of said outer cylinder and said casing in a locked condition of the lock, third means in said casing, said outer tubular cylinder, and said front cylinder preventing relative rotation thereof while the lock is in a locked condition, fourth means in said casing, said outer tubular cylinder and said intermediate cylinder preventing relative rotation thereof in a locked condition of the lock, said front cylinder, said intermediate cylinder, and said final cylinder being formed with respective keyways into which said first, third, and fourth means project operatively, said front cylinder and said intermediate cylinder having initial positions in which their keyways are aligned and in which their keyways are out of alignment with the keyway of said final cylinder, first spring means operatively engaging said outer tubular cylinder and second spring means operatively engaging said final cylinder for returning said front cylinder and said intermediate cylinder to their initial positions after operation.

8. A cylinder lock of the character described comprising a relatively stationary casing formed with a bore, an outer tubular cylinder rotatable in said bore, a front cylinder, an intermediate cylinder, and a final cylinder rotatably mounted in the bore of said tubular outer cylinder, a locking bolt operating element on said final cylinder, first means engaging said final cylinder, said outer tubular cylinder, and said casing for holding said final cylinder and said outer tubular cylinder and said casing from rotating relative to each other in a locked condition of the lock, second means in said casing and said outer tubular cylinder preventing relative rotation of said outer cylinder and said casing in a locked condition of the lock, third means in said casing, said outer tubular cylinder, and said front cylinder preventing relative rotation thereof while the lock is in a locked condition, fourth means in said casing, said outer tubular cylinder and said intermediate cylinder preventing relative rotation thereof in a locked condition of the lock, said front cylinder, said intermediate cylinder, and said final cylinder being formed with respective keyways into which said first, third, and fourth means project operatively, said front cylinder and said intermediate cylinder having initial positions in which their keyways are aligned and in which their keyways are out of alignment with the keyway of said final cylinder, the keyways of said front and intermediate cylinders being arranged to receive a key for operating the corresponding means to release these cylinders for rotation by the key to align their keyways with the keyway of the final cylinder.

9. A cylinder lock of the character described comprising a relatively stationary casing formed with a bore, an outer tubular cylinder rotatable in said bore, a front cylinder, and intermediate cylinder, and a final cylinder rotatably mounted in the bore of said tubular outer cylinder, a locking bolt operating element on said final cylinder, first means engaging said final cylinder, said 70
75

outer tubular cylinder, and said casing for holding said final cylinder and said outer tubular cylinder and said casing from rotating relative to each other in a locked condition of the lock, 5 second means in said casing and said outer tubular cylinder preventing relative rotation of said outer cylinder and said casing in a locked condition of the lock, third means in said casing, said outer tubular cylinder, and said front cylinder preventing relative rotation thereof while the lock is in a locked condition, fourth means in said casing, said outer tubular cylinder and said intermediate cylinder preventing relative rotation thereof in a locked condition of the lock, 10 said front cylinder, said intermediate cylinder and said final cylinder being formed with respective keyways into which said first, third, and fourth means project operatively, said front cylinder and said intermediate cylinder having initial positions in which their keyways are aligned and in which their keyways are out of alignment with the keyway of said final cylinder, the keyways of said front and intermediate cylinders being arranged to receive a key for operating the 15 corresponding means to release these cylinders for rotation by the key to align their keyways with the keyway of the final cylinder, the keyway of the final cylinder then being conditioned to receive said key to operate the corresponding 20 means to connect said final cylinder and said outer tubular cylinder while disconnecting said outer tubular cylinder from said casing, thereby enabling locking bolt operating rotation of said final cylinder by said key.

10. A cylinder lock of the character described comprising an outer casing including a bore, an outer tubular cylinder revolvable in said bore, a front cylinder rotatable in the bore of the outer cylinder spring means in said bore for engaging said outer tubular cylinder and the front cylinder toward initial position, an intermediate cylinder in said bore behind the front cylinder, and a rear or final cylinder in said bore behind the intermediate cylinder, spring means connecting the final cylinder and the intermediate cylinder and tensioning the same toward initial positions.

11. A cylinder lock of the character described comprising an outer casing including a bore, an outer tubular cylinder revolvable in said bore, a front cylinder rotatable in the bore of the outer cylinder spring means in said bore for engaging said outer tubular cylinder and the front cylinder for rotating the front cylinder toward initial position, an intermediate cylinder in said bore behind the front cylinder, and a rear or final cylinder in said bore behind the intermediate cylinder, spring means connecting the final cylinder and the intermediate cylinder and tensioning the same toward initial positions, said front and intermediate cylinders having keyways normally aligned in the initial position of the front and intermediate cylinders, said final cylinder having a keyway normally crossed with respect to the first-mentioned keyway in the initial position of the final cylinder.

12. A cylinder lock of the character described comprising an outer casing including a bore, an outer tubular cylinder revolvable in said bore, a front cylinder rotatable in the bore of the outer cylinder spring means in said bore for engaging said outer tubular cylinder and the front cylinder for rotating the front cylinder toward initial position, an intermediate cylinder in said bore behind the front cylinder, and a rear or final

cylinder in said bore behind the intermediate cylinder, spring means connecting the final cylinder and the intermediate cylinder and tensioning the same toward initial positions, said front and intermediate cylinders having keyways normally aligned in the initial position of the front and intermediate cylinders, said final cylinder having a keyway normally crossed with respect to the first-mentioned keyways in the initial position of the final cylinder, said outer casing, said outer cylinder and said front cylinder and said intermediate cylinder containing radially movable pin means adapted to be positioned by the insertion of a key in the keyways of the front and intermediate cylinders, said means normally locking the mentioned cylinders against relative rotation.

13. A cylinder lock of the character described comprising an outer casing including a bore, an outer tubular cylinder revolvable in said bore, a front cylinder rotatable in the bore of the outer cylinder spring means in said bore for engaging said outer tubular cylinder and the front cylinder for rotating the front cylinder toward initial position, an intermediate cylinder in said bore behind the front cylinder, and a rear or final cylinder in said bore behind the intermediate cylinder, spring means connecting the final cylinder and the intermediate cylinder and tensioning the same toward initial positions, said front and intermediate cylinders having keyways normally aligned in the initial position of the front and intermediate cylinders, said final cylinder having a keyway normally crossed with respect to the first-mentioned keyways in the initial position of the final cylinder, said outer casing, said outer cylinder and said front cylinder and said intermediate cylinder containing radially movable pin means adapted to be positioned by the insertion of a key in the keyways of the front and intermediate cylinders, said means normally locking the mentioned cylinders against relative rotation, said outer casing and outer cylinder containing further pin means riding on the exterior of the front cylinder and of the intermediate cylinder and adapted to be operated by some of the first mentioned pin means in a subsequent position of the front and intermediate cylinders.

14. A cylinder lock of the character described comprising an outer casing including a bore, an outer tubular cylinder revolvable in said bore, a front cylinder rotatable in the bore of the outer cylinder spring means in said bore for engaging said outer tubular cylinder and the front cylinder for rotating the front cylinder toward initial position, an intermediate cylinder in said bore behind the front cylinder, and a rear or final cylinder in said bore behind the intermediate cylinder, spring means connecting the final cylinder and the intermediate cylinder and tensioning the same toward initial positions, said front and intermediate cylinders having keyways normally aligned in the initial position of the front and intermediate cylinders, said final cylinder having a keyway normally crossed with respect to the first-mentioned keyways in the initial position of the final cylinder, said outer casing, said outer cylinder and said front cylinder and said intermediate cylinder containing radially movable pin means adapted to be positioned by the insertion of a key in the keyways of the front and intermediate cylinders, said means normally locking the mentioned cylinders against relative rotation, said outer casing and outer

- cylinder containing further pin means riding on the exterior of the front cylinder and of the intermediate cylinder and adapted to be operated by some of the first mentioned pin means in a 5 subsequent position of the front and intermediate cylinders, said outer casing, said outer cylinder and said final cylinder containing radially movable pin means adapted to be positioned by the insertion of a key in the keyways of the front 10 and intermediate cylinders, the rotation of said front cylinder and said intermediate cylinder effecting alignment of the keyways in said front cylinder, said intermediate cylinder and said final cylinder, the further insertion of the key means into the keyway of said final cylinder operating said pin means in said outer casing, said outer cylinder, said front cylinder said intermediate cylinder, and said final cylinder, said pin means normally locking said cylinders against relative rotation.

FREDERICK W. KENNEY. 10
